United States Patent Office

Des. 216,216
Patented Dec. 2, 1969

216,216

PITCHER

Louis Kriegel, Flushing, N.Y., assignor to Joy Plastics,
Inc., New York, N.Y., a corporation of New York

Filed May 24, 1968, Ser. No. 12,068

Term of patent 14 years

Int. Cl. D7—01

U.S. Cl. D44—21

FIG. 1

FIG. 2

FIG. 3

FIG. 4

FIG. 5

FIG. 6

FIG. 1 is a side elevational view of a pitcher showing my new design;

FIG. 2 is a top plan view;

FIG. 3 is a rear elevational view;

FIG. 4 is a front elevational view;

FIG. 5 is a bottom plan view; and

FIG. 6 is a perspective view of a pitcher showing another form of my new design wherein the cover, handle top and pouring portion have been modified.

I claim:

The ornamental design for a pitcher, as shown and described.
